UNITED STATES PATENT OFFICE.

GILMAN H. PIERCE, OF LEOMINSTER, MASSACHUSETTS.

TOY TERMINAL.

1,278,203.

Specification of Letters Patent. Patented Sept. 10, 1918.

Application filed April 6, 1918. Serial No. 226,969.

To all whom it may concern:

Be it known that I, GILMAN H. PIERCE, a citizen of the United States, residing at Leominster, in the county of Worcester and

5 State of Massachusetts, have invented a new and useful Toy Terminal, of which the following is a specification.

This invention relates to devices for supporting and guiding a rolling marble or ball 10 in a manner to stimulate interest in a young child.

It is the object of my invention to provide a toy of this character which shall possess important features of interest and 15 novelty; which shall be simple in construction and durable when in use; and which shall afford the variety of operation necessary to fix and retain a child's attention.

With these general objects in view, my 20 invention relates to a toy terminal having a plurality of successively branched guide ways leading to terminal pockets.

My invention further relates to means for controlling the course of the rolling marble 25 or ball as it enters said guide ways, preferably from an inclined runway associated therewith. Such controlling means may conveniently consist of a number of small pivoted switches, and certain of these switches 30 may be arranged for distant control. These switches constitute an important part of my invention.

My invention further relates to arrangements and combinations of parts hereinafter 35 described and more particularly pointed out in the appended claims.

A preferred form of my invention is shown in the drawings, in which—

Figure 1 is a plan view of my toy terminal;

Fig. 2 is a partial side elevation taken as indicated by the arrows 2 in Fig. 1;

Fig. 3 is a detail plan view, partly in section, showing the means for connecting several parts together;

Fig. 4 is an enlarged detail plan view of one of the switches, and

Fig. 5 is a detail sectional view on the line 5—5 of Fig. 4.

50 Referring to the drawings, my improved toy comprises a runway 10, a base preferably formed in two parts 11 and 12, and a curved connecting member 13 for joining the runway 10 to the base member 12. The several 55 parts 10, 11, 12 and 13 may most conveniently be formed with detachable connec-

tions, a simple type of connection being indicated in Fig. 3 and consisting merely of pins or dowels 14 adapted to be received in corresponding holes 15.

60

The connecting member 13 may be raised and supported upon a block 16, this giving the base member 12 a slightly inclined position. The runway 10 is also supported upon a block 17 of greater height than the block 16 so that the runway is downwardly inclined toward the member 13. The runway and connecting member are both formed with a pair of raised ribs 18 forming a track for a rolling marble or ball. The base members 11 and 12 are each provided with a plurality of such ribs which may have the general outline and position indicated in the drawings, in which it will appear that these ribs form guide ways connecting with the ribs 18 and successively branched as they recede therefrom. At the extreme end of the base member 11 a cross piece 19 is provided, thus forming a plurality of pockets at the ends of the guide ways.

75

At the entrance of each branch guide way, one of the supporting ribs is cut off, and a switch 20 is pivotally secured to the base as at 21. The switches are preferably formed with the general outline shown in Fig. 4, in which it will be seen that the switch has one straight side surface 22 and a curved side surface 23 opposite thereto. The pivot 21 is preferably nearer the rear end of the switch, and the switch tapers more gradually from the pivot toward the longer front end thereof. These switches are movable manually and may be set by the child in any desired combination.

80

When it is desired to guide a rolling ball from a straight guide way to a branch guide way, the switch is set in the position indicated in full lines in Fig. 4. If, on the other hand, it is desired that the ball shall continue along the straight guide way, the switch is set in the position indicated in dotted lines in Fig. 4.

95

While this type of switch is desirable, it is not in all cases essential that this type should be used, and I have indicated at 24 in Fig. 1 a different type of switch which may also be used, particularly when a guide way is branched at a point where the track is curved. The switches 24 are pivoted adjacent their rear ends and taper gradually to the opposite end. They may also be curved in general outline to conform to the

105

110

general curvature of the track at the point where they are to be used.

I have also devised means by which certain of the switches, as 20^a and 20^b, may be controlled from a distant point. For this purpose studs 25 and 26 are fixed in the switches, extending downward through slots 27 (Fig. 4) in the base 12. Cords 28 and 29 attached to the lower ends of the studs 25 and 26 pass through guides in the form of screw eyes 30, and extend therefrom longitudinally of the base 12. Grooves 31 may be provided for the passage of the cords across the underside of the base section 11, the ends of the cords being brought out through holes in the side of the section 11 and being provided with suitable buttons or pull pieces 32 and 33. Two cords and buttons are provided for each switch 20^a and 20^b, and the switch can be moved to either position by pulling on the corresponding cord. The mechanism described for moving the switch is illustrative only and I do not wish to be restricted to the precise mechanism herein shown.

It will be understood that the arrangement of the straight and branch guide ways may be infinitely varied and multiplied, and that the arrangement in the drawings is illustrative only.

Having thus described my invention, it will be evident to those skilled in the art that other changes and modifications can be made therein without departing from the spirit and scope of my invention as set forth in the claims, and I do not wish to be otherwise limited to the details herein disclosed, but what I do claim is:—

1. A toy terminal comprising an inclined runway, a plurality of successively branched guide ways connected to said runway, and switches controlling entrance to said guide ways.

2. A toy terminal comprising an inclined runway, a plurality of successively branched guide ways connected to said runway, and means to guide a rolling ball from said runway along any desired course through said guide-ways.

3. A toy terminal comprising an inclined runway, a plurality of successively branched

guide ways connected to said runway and leading to terminal pockets, and a switch controlling the entrance to each branch guide way.

4. A toy terminal comprising an inclined runway, a plurality of successively branched guide ways connected to said runway and leading to terminal pockets, and manually adjustable switches effective to determine the particular pocket which shall receive a ball approaching said pockets from said runway.

5. In a toy terminal, a switch block pivotally fixed at a point between its ends, said block having one straight and one curved side and tapering very gradually toward its longer front end and more abruptly toward its shorter rear end.

6. A toy terminal comprising a base having a plurality of ribs thereon forming guide ways and pockets for a rolling ball, switches pivotally mounted on said base at the ends of said ribs and co-operating with the next adjacent rib on each side thereof to determine the path of the ball, and an inclined runway from which a rolling ball may be guided by said ribs and switches to any selected pocket.

7. A toy terminal comprising a plurality of successively branched guide ways, means to roll a ball along said guide ways, a separate switch controlling the entrance to each branch guide way, and means to operate certain of said switches from a distant point.

8. A toy terminal comprising a base having a plurality of successively branched guide ways thereon, said guide ways being adapted to support a rolling ball, a manually adjustable switch controlling the entrance to each branch guide way, and means to control certain of said switches from a distant point, said means comprising cords connected to said switches and guides for said cords beneath said base, the ends of said cords extending through suitable openings in the base and being secured to pull-pieces outside of said openings.

In testimony whereof I have hereunto affixed my signature.

GILMAN H. PIERCE.
